UNITED STATES PATENT OFFICE.

THOMAS C. KATKE, OF MILWAUKEE, WISCONSIN, ASSIGNOR TO BUNDE & UPMAYER CO., OF MILWAUKEE, WISCONSIN, A CORPORATION OF WISCONSIN.

DESIGN FOR A BADGE, BUTTON, CHARM, EMBLEM, PIN, OR ARTICLE OF SIMILAR NATURE.

61,197.

Specification for Design.

Patented July 11, 1922.

Application filed February 20, 1922. Serial No. 786. Term of patent 7 years.

To all whom it may concern:

Be it known that I, THOMAS C. KATKE, a citizen of the United States, residing at Milwaukee, in the county of Milwaukee and State of Wisconsin, have invented a new, original, and ornamental Design for Badges, Buttons, Charms, Emblems, Pins, or Articles of Similar Nature, of which the following is a specification, reference being had to the accompanying drawing, forming part thereof.

In the drawing:

Fig. 1 is a front view, Fig. 2 is a rear view and Fig. 3 is an edge view of the badge, button, charm, emblem, pin or article of similar nature, showing my new design.

I claim:

The ornamental design for a badge, button, charm, emblem, pin, or article of similar nature, as shown.

THOMAS C. KATKE.

Witnesses:

EDWIN E. OLSON,
CARL A. HAHN.
